UNITED STATES PATENT OFFICE

JOHN McDONOUGH AND LARS NORMANN, OF CHICAGO, ILLINOIS, ASSIGNEES TO
WESTERN ELECTRIC COMPANY, INCORPORATED, OF NEW YORK, N. Y., A CORPORA-
TION OF NEW YORK

APPARATUS FOR REMOVING CONNECTING ELEMENTS

Application filed April 25, 1930. Serial No. 447,400.

This invention relates to apparatus for removing connecting elements, and more particularly to apparatus for removing wires attached to electrical apparatus which is to be repaired.

Before electrical equipment can be repaired, it is often necessary that the conductors attached thereto be removed from the terminals thereof and, for example, when a plurality of relays, resistance units or like equipment are mounted in groups on a common mounting plate adapted to support a row of such equipment, it is necessary to remove the conductors extending from a formed cable to the terminals thereof.

An object of the invention is the provision of a simple and efficient apparatus for expeditiously removing connecting elements.

In accordance with one embodiment, the invention contemplates an apparatus for removing wires from the terminals of electrical equipment mounted upon common mounting plates wherein the mounting plate with the apparatus mounted thereon is advanced past an oscillatory member having a slotted portion for engaging wires attached to the electrical apparatus adjacent the terminals or binding posts thereof, thereby to bend the wires back and forth to break them off. The oscillatory member is provided with a knife edge for cutting transverse wires which might join adjacent terminals, and control apparatus is provided whereby after a mounting plate has been secured in the apparatus and advanced past the oscillatory member to sever the wires from the terminals, the mounting plate and the carriage provided therefor will be retracted to their original position, and the advancing mechanism automatically rendered inoperative.

It is believed that a complete understanding of the invention may be had by referring to the following detailed description when considered in conjunction with the accompanying drawings, wherein

Fig. 1 is a plan view of the apparatus, parts being broken away for the sake of clarifying the drawing;

Fig. 2 is a side elevational view of the apparatus shown in Fig. 1 with the exception

that the mounting plate has been removed from the apparatus, and some of the parts omitted from Fig. 1 have been added;

Fig. 3 is an enlarged fragmentary plan view of the apparatus showing the oscillatory member and its actuating mechanism; 55

Fig. 4 is a vertical sectional view taken on the line 4—4 of Fig. 3 in the direction of the arrows showing a mounting plate which has been advanced part of the way through the apparatus;

Fig. 5 is a transverse vertical sectional view taken on the line 5—5 of Fig. 4 in the direction of the arrows, and

Fig. 6 is a fragmentary vertical sectional view taken on the line 6-6 of Fig. 1 in the direction of the arrows showing a part of the automatic control means. 65

Referring now to the drawings wherein like reference characters designate the same parts throughout the several views, the numerals 1 and 2 designate side plates which cooperate with angle members 3 and 4 and a base plate 5 to form a channel shaped structure having its upper edges extending inwardly toward the center of the channel. This channel shaped structure may be mounted upon a bench or table (not shown), and constitutes the guiding means for directing a mounting plate 9 past an oscillatory member 10 comprising a part of an oscillating assembly designed generally by the numeral 11.

Slidably mounted upon the angle members 3 and 4 is a carriage designated generally by the numeral 12 for supporting and advancing the mounting plate 9. The carriage 12 comprises top plates 13, 14, and 15 having secured thereto and being spaced apart by spacers 19 and 20 (Fig. 5). Secured to the underside of the spacers 19 and 20 are clamping plates 21 and 22, respectively, which cooperate with the spacers 19 and 20 and the top plates 13, 14, and 15, to form a plurality of grooves into which angle members 3 and 4 extend thereby to position the carriage 12 in place on the angle members 3 and 4 so as to permit it to be slid longitudinally of the angle members 3 and 4, but restraining it from transverse movement. Secured to the underside of the clamping plate 21 is

a rack 23 which meshes with a pinion gear 24 mounted upon a shaft 25, for advancing the carriage 12 past the oscillating assembly 11 and for retracting it to the position shown in Fig. 1 upon rotation of the pinion gear 24 in opposite directions.

The shaft 25, upon which the pinion gear 24 is mounted, is journalled in the side plate 2, and in a housing 29 which encloses a beveled gear 30 pinned to the shaft 25, and a beveled gear 31 which meshes with the beveled gear 30 and is pinned to a shaft 32. The shaft 32 is journalled in the housing 29, and drives the beveled gear 30. The other end of the shaft 32 is journalled in the side of a transmission housing 33 and may be driven in either of two directions through a clutch mechanism designated generally by the numeral 34 and mounted within the transmission housing 33.

A shaft 38, having a beveled gear 39 (Fig. 1) secured thereto which meshes with the beveled gear 40 mounted upon a shaft 41 constantly driven by an electrical motor 42, may be interconnected with the shaft 32 to drive the shaft 32 in either of two directions by means of the clutch 34 (Fig. 6) the following mechanism being provided for interconnecting the shafts 38 and 32. A driving member 43 is splined to the shaft 38 at 44 and has mounted on opposite faces thereof clutch teeth 45 and 46 which, upon movement of the driving member to the right or left, respectively, will engage clutch teeth 47 or 48, respectively. The clutch teeth 47 are formed upon a disk fastened to gear pinion 49, which is pinned to the shaft 32 at 50. Gear teeth 51 mesh with the teeth of an idler 52, rotatable about a stud shaft 53 mounted in the side of the transmission housing 33.

The driving member 43 has an annular groove 56 formed therein, in which a roller 57 rides. The roller 57 is mounted upon the upper end of the lever 58 mounted upon a shaft 59 and adapted to be oscillated in a clockwise or counterclockwise direction in the manner to be described hereinafter so as to move the driving member 43 to the right or left (Fig. 6). The idler 52 meshes with a pinion 60, mounted upon a shaft 61 journalled in the sides of the transmission housing 33 and having pinned thereto a pinion 62 which meshes with a driving gear 63 freely rotatable upon the shaft 38 and being restrained from movement longitudinally of the shaft 38 by a key 64 which engages an annular slot 66 formed in the shaft. The clutch teeth 48 are formed upon a clutch plate 65 which is fixed to the driving gear 63. Upon rotation of the shaft 59 in a clockwise direction (Fig. 6), it will be apparent that the clutch teeth 45 will engage the teeth 47 to drive the shaft 32 in one direction, and upon movement of the shaft 59 in a counter-

clockwise direction, the teeth 46 will engage the teeth 48 to drive the shaft 32 in the opposite direction through the driving gear 63, pinion 62, shaft 61, pinion 60, idler 52 and pinion 49.

The shaft 59 extends through the side of the transmission housing 33 and the side plates 2 and 1 and has a lever 69 mounted thereon outside of the channel formed by the plates 1 and 2. A lever 70 is also secured to the shaft 59 inside the channel and has a tension spring 71 secured thereto at one end, its other end being secured to the plate 1 at 72, tending to rotate the shaft 59 in a counterclockwise direction (Fig. 2) and to hold the clutch teeth 46 in engagement with the clutch teeth 48 to drive the carriage 12 to the right (Figs. 1 and 2). The lever 69 may be moved manually in a clockwise direction (Fig. 2) against the action of the spring 71, and upon being so moved will move the clutch teeth 45 into engagement with the clutch teeth 46 to drive the carriage 12 to the left (Fig. 1).

Fixed to the lever 70 intermediate its ends is one end of a link 73, the other end of which is pinned to a lever 74 rotatably mounted on the side plate 1 at 75. The lever 74 carries a cam member 79 adapted to engage a roller 80 positioned upon a cam lever 81 which is pivotally mounted at 82 on a latch supporting plate 83. The latch supporting plate 83 has slidably therein a plunger 84 having a flange 85 formed thereon. A shoulder 86 is formed on the latch supporting plate 83, and a spring 87 is positioned between flange 85 and shoulder 86 for normally urging the plunger 84 upwardly (Fig. 2). Formed on the cam lever 81 is a yoke 91 which engages the upper surface of the flange 85 of the plunger 84, and is adapted to move the plunger downwardly against the action of the spring 87 when the cam member 79 engages the roller 80 to rock the cam lever 81 in a clockwise direction (Fig. 2). When the carriage 12 is in the extreme right hand position (Fig. 2), the plunger 84 is adapted to engage a slot 92 formed in a plate 93 secured to the under side of the clamping plate 22, thereby to lock the carriage in that position so as to prevent accidental displacement thereof.

The shaft 59 has a gear segment 94 secured thereto between the lever 69 and the outer surface of the plate 1, engaging with teeth 95 in a rod 96 which is reciprocable in guide members 97 and 98. At its left end (Fig. 1) the rod 96 has a portion thereof cut away to form a shoulder 100 which is adapted to be engaged by a latch 101 formed on a bell crank lever 102. The bell crank lever 102 is pivoted at 103 and is urged to rotate in a clockwise direction (Fig. 1) by a compression spring 104 positioned between an arm of the lever 102 and the side plate 1. Another arm 108 of the bell crank lever 102 extends trans-

versely of the angle member 3 and into the path of a pin 109 mounted upon the top plate 15 of the carriage 12. Upon movement of the lever 69 to the right (Figs. 1 and 2) the rod 96 will be moved to a point where the 5 shoulder 100 will be to the right of the latch member 101 formed on the bell crank 102, whereupon the spring 104 will move the latch member 101 into the cutaway portion of the rod 96, to thereby hold the rod 96 in its extreme right hand position until the carriage 10 12 has been advanced past the oscillating assembly 11 and the pin 109 engages the arm 108 of the bell crank 102 to release the latch member 101, thereby to permit the spring 71 15 to rotate the shaft 59 in a counterclockwise direction (Fig. 2) to reverse the clutch 34, so as to drive the carriage back to its original position.

Just prior to the time when the carriage 12 reaches the position shown in Figs. 1 and 2, a depending projection 110 formed on the under side of the clamping plate 22 will engage the upper end of the lever 74 to move it to the right (Fig. 2), and since the lever 74 is connected by the link 73 to the lever 70, the shaft 59 will be rotated in a clockwise direction (Figs. 2 and 6) to move the driving member 43 of the clutch 34 into its intermediate position as shown in Fig. 6, where its clutch teeth 45 and 46 are out of engagement with their associated clutch teeth 47 and 48. In being retracted to the position shown in Fig. 2, the carriage 12 will carry the plate 93 which has a cam surface 111, part way past the plunger 84, and the cam surface 111 will engage the plunger 84 to compress the spring 87 to move the plunger downwardly until the upper end of the plunger registers with the depression 92 in the plate 93, whereupon the spring 87 will move the plunger 84 upwardly to lock the carriage in the position shown in Fig. 2.

From the foregoing, it will be apparent that a mounting plate which has been secured to the carriage 12 by means of a clamping member 112, may be advanced past the oscillating assembly 11 and automatically retracted to its original position as shown in Figs. 1 and 2, in response to the movement of the lever 69 to the right (Figs. 1 and 2), and in being so moved, the oscillating assembly which will now be described, will break any connecting elements attached to the equipment mounted on the mounting plate. For the sake of illustration, the mounting plate 9 has been shown as having a plurality of relays 116 secured thereto by any suitable means and having their terminals 117 extending through apertures 118 in the plate 9. In this type of electrical equipment connecting elements or wires 126 running to the terminals of the electrical apparatus are usually formed into a cable such as that designated by numeral 119, and the terminals 117 are ar-

ranged in two rows as shown in Figs. 1 and 2.

The oscillating assembly 11 comprises a plate 120 pivoted on a threaded member 121 which is secured to a supporting bar 122 suspended from a cross member 123 which is supported at its outer edges on spacers 124 and 125 which in turn are secured to the upper surface of the angle members 3 and 4, respectively, (Fig. 5). The supporting bar 122 has a pair of guide members 129 secured thereto which direct the connecting elements or wires 126 upwardly into engagement with a guide member 130 secured to the right end (Fig. 4) of the plate 120. Secured to the guide member 130 and extending downwardly between the guide members 129 is a knife 131 adapted to sever any strap wires such as that shown at 132 (Fig. 5) connecting terminals on opposite sides of a relay, as the mounting plate 9 is advanced past the oscillating assembly 11. The plate 120 is formed with two tapering slots as shown at 133 and wires 126 which have engaged the guide members 129 and 130 due to the advancement of the mounting plate 9 toward the oscillating assembly 11, will be directed into one or the other of these slots.

The plate 120 has secured thereto, by means of screws 137, a vertically extending semi-cylindrical member 138 in which is freely rotatable and reciprocable a piston-like member 139. Formed in the piston-like member 139 is an aperture 140 in which a pin 141 is rotatably mounted. The pin 141 is fixed eccentrically on a shoulder 142 of a shaft 143 journaled in journal blocks 147 and 148 secured to the supporting cross member 123. A beveled gear 149 is pinned to the shaft 143 and meshes with a beveled gear 150 mounted upon a shaft 151 journaled in journal blocks 152 and 153 (Fig. 3). Attached to the end of the shaft 151 opposite to that on which the beveled gear 150 is mounted, is a pulley 154 connected by means of a belt 155 to a driving pulley 156 secured to the end of the shaft 41 driven by the motor 42.

Upon rotary motion being imparted to the shaft 143 through the gears and pulley described hereinbefore, the pin 141 will be driven in a circular path, and will move the piston-like member 139 up and down in the vertically extending semi-cylindrical member 138 and will simultaneously oscillate the plate 120, to which the semi-cylindrical member 138 is attached, about member 121. The gears 149, 150, and the cylindrical member 138 together with its cooperating mechanism, are enclosed in a housing 160, the right end of which (Figs. 1, 2, and 4) is inclined downwardly to a point just below the upper edge of the knife 131, forming an inclined surface 161 for directing the cable 119 and wires 126 upwardly.

A better understanding of the invention described hereinbefore will be had from the

following brief description of the operation thereof. Assuming that the carriage 12 is in the position shown in Figs. 1 and 2, a mounting plate 9 having a plurality of relays 116 mounted thereon, may be positioned on the carriage and secured in place by the clamping members 112. It will be assumed that at this time the electric motor 42 has been started and is driving the oscillating plate 120 through the belt 155, gears 150 and 149 and the cooperating piston-like member 139 and semi-cylindrical member 138, the operation of which is believed to be apparent. With the mounting plate 9 secured on the carriage 12, the lever 69 may be moved to the right (Fig. 2) to rotate the shaft 59 in a clockwise direction (Figs. 2 and 6) to move the clutch teeth 45 into engagement with the clutch teeth 47 to drive the carriage 12 to the left (Figs. 1, 2, 3, and 4). In moving the lever 69 to the right (Fig. 2), the levers 70 and 74 will also be moved to the right, causing the cam member 79 to engage the roller 80, thereby to move the plunger 84 out of its associated slot 92 in the plate 93 secured to the underside of the carriage 12, and the segmental gear 94 will be moved to the right drawing with it the rod 96 to a point where the latch 101 will engage the shoulder 100 and hold the rod 96 in its extreme right hand position (Figs. 1 and 2). In this manner the carriage 12 will be advanced past the oscillating assembly 11 and, in passing the wires or connecting elements 126, will be directed by the guide members 129 and 130 into the slots 133 formed in the plate 120, and will be moved back and forth due to the oscillation of the plate 120. In being moved back and forth by the plate 120, the wires or connecting elements 126 will be bent back and forth to break the wires at a point adjacent the terminals 117, and any strap wires 132 which connect oppositely disposed terminals 117, will be cut by the knife 131. As the carriage 12 approaches the left end (Figs. 1 and 2) of the channel formed by the angle members 3 and 4, the pin 109 on the carriage 12 will engage the lever 108 and move it to the left (Fig. 1) releasing the latch member 101 and permitting the spring 71 to actuate the lever 70 so as to move the clutch teeth 45 out of engagement with the clutch teeth 47, and move the clutch teeth 46 into engagement with the clutch teeth 48, thereby driving the shaft 32 in the opposite direction. The shaft 32, in rotating in the opposite direction, will drive the carriage 12 to the right to the position shown in Figs. 1 and 2. Just prior to the time when the carriage 12 reaches the position shown in Figs. 1 and 2, the depending projection 110 thereon will engage the upper end of the lever 74 and move it together with the lever 70 to the right (Fig. 2), thereby moving the clutch driving member 43 into a position where the teeth 45 and 46 thereof are not in engagement with either the

teeth 47 or the teeth 48, whereupon the plunger 84 will engage its associated depression 92 to lock the carriage in the position shown in Figs. 1 and 2 until the lever 69 is again operated manually.

Although this invention has been described as pertaining to a specific type of apparatus for removing connecting elements from a particular type of electrical equipment, it is to be understood that the invention is not limited in scope to such apparatus or equipment, but only as defined in the appended claims.

What is claimed is:

1. In an apparatus for removing connecting elements from the terminals of electrical equipment, an oscillatory member having a slotted portion for engaging connecting elements therein to break them, and means for advancing the electrical equipment past the oscillatory member and automatically retracting it to its original position.

2. In an apparatus for removing connecting elements from the terminals of electrical equipment, an oscillatory member having a slotted portion for engaging connecting elements therein to break them, means for advancing the electrical equipment past the oscillatory member and automatically retracting it to its original position, and means for automatically rendering the advancing means inoperative upon the retraction of the electrical equipment to its original position.

3. In an apparatus for removing connecting elements from the terminals of electrical equipment, a slotted member for engaging the connecting elements adjacent the terminals, means for oscillating the slotted member to break the connecting elements, a carriage for supporting the electrical equipment, and means for advancing the carriage past the slotted member and automatically retracting it.

4. In an apparatus for removing connecting elements from the terminals of electrical equipment comprising an oscillatable member having a slotted portion for engaging the connecting elements adjacent the terminals to break the elements from the terminals, means including an eccentric for oscillating the oscillatable member, and means for advancing the electrical equipment past the oscillatable member.

5. An apparatus for removing connecting elements from the terminals of electrical equipment, comprising an oscillatable member having a slotted portion for engaging the connecting elements adjacent the terminals to break the elements from the terminals, means positioned on the oscillatable member for cutting strap wires, means including an eccentric for oscillating the oscillatable member, and means for advancing the electrical equipment past the oscillatable member.

6. An apparatus for removing connecting

elements from the terminals of electrical equipment comprising an oscillatory member having a slotted portion for engaging the connecting elements to bend and break them, means for advancing the electrical equipment past the oscillatory member including a carriage for supporting the electrical equipment, driving means, a clutch associated therewith, manually controlled means for operating the clutch in one direction to advance the carriage past the oscillatory member, and automatically operable means for operating the clutch in the opposite direction to retract the carriage to its original position.

7. An apparatus for removing connecting elements from the terminals of electrical equipment comprising an oscillatory member having a slotted portion for engaging the connecting elements to bend and break them, means for advancing the electrical equipment past the oscillatory member including a carriage for supporting the electrical equipment, driving means, a clutch associated therewith, manually controlled means for operating the clutch in one direction to advance the carriage past the oscillatory member, automatically operable means for operating the clutch in the opposite direction to retract the carriage to its original position, and means for locking the carriage against accidental displacement from its retracted position.

8. An apparatus for removing connecting elements from the terminals of electrical equipment comprising an oscillatory member having a slotted portion for engaging the connecting elements to bend and break them, means for advancing the electrical equipment past the oscillatory member including a carriage for supporting the electrical equipment, driving means, a clutch associated therewith, manually controlled means for operating the clutch in one direction to advance the carriage past the oscillatory member, automatically operable means for operating the clutch in the opposite direction to retract the carriage to its original position, and means controlled by the carriage for reversing the clutch to cause the driving means to retract the carriage to its original position.

9. An apparatus for removing connecting elements from the terminals of electrical equipment comprising an oscillatory member having a slotted portion for engaging the connecting elements to bend and break them, means for advancing the electrical equipment past the oscillatory member including a carriage for supporting the electrical equipment, driving means, a clutch associated therewith, manually controlled means for operating the clutch in one direction to advance the carriage past the oscillatory member, and means operated by the carriage upon reaching a pre-

determined position for reversing the direction of travel of the carriage.

10. An apparatus for removing connecting elements from the terminals of electrical equipment comprising an oscillatory member having a slotted portion for engaging the connecting elements to bend and break them, means for advancing the electrical equipment past the oscillatory member including a carriage for supporting the electrical equipment, driving means, a clutch associated therewith, manually controlled means for operating the clutch in one direction to advance the carriage past the oscillatory member including a carriage for supporting the electrical equipment, driving means, a clutch associated therewith, manually controlled means for operating the clutch in one direction to advance the carriage past the oscillatory member, means operated by the carriage upon reaching a predetermined position for reversing the direction of travel of the carriage, and means for operating the clutch to render the driving means inoperative when the carriage is retracted to its original position.

11. An apparatus for removing connecting elements from electrical equipment comprising an oscillating means for bending and breaking the connecting elements adjacent the terminals, means for advancing and retracting the electrical equipment past the oscillating means comprising driving means, manually controlled means for rendering the driving means effective to advance the electrical equipment, and automatic means for retracting the electrical equipment and locking it in its retracted position.

In witness whereof, I hereunto subscribe my name this 17th day of April, A. D. 1930.

JOHN McDONOUGH.

In witness whereof, I hereunto subscribe my name this 19th day of April, A. D. 1930.
